(57) CLAIM

The ornamental design for a hanger, as shown and described.

DESCRIPTION

FIG. 1 is a perspective view of a hanger in a first configuration;

FIG. 2 is a front view thereof in the first configuration;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front view of the hanger in a second configuration.

The broken lines shown represent subject matter that forms no part of the claimed design.

1 Claim, 8 Drawing Sheets
